COLLAPSIBLE IRONING TABLE

Walter L. Anderson, Wichita, Kans.

Application December 3, 1951, Serial No. 259,535

2 Claims. (Cl. 38—129)

1

This invention relates to an ironing table which is adapted to be folded when not in use.

The present invention comprises an improvement over the ironing table disclosed in my Patent No. 2,567,538, issued September 11, 1951 and entitled "Collapsible Ironing Table."

It is an object of the present invention to provide an improved collapsible ironing table which is readily installed, which is steady and firm in unfolded position, and which is composed of a minimum number of parts for ease in manufacture and assembly.

It is another object of the present invention to provide a collapsible ironing table which is readily assembled and disassembled by the ultimate user thereof and wherein the ironing board subassembly can be readily detached for use in other locations and wherein the ironing board subassembly is adapted to lie flat on a table or the like.

Other and further important objects of this invention will be apparent from the disclosures in the specification, and in the accompanying drawings, in which:

Figure 1 is a side elevational view of a collapsible ironing table embodying the principles of the present invention, with the ironing table in unfolded position and showing the ironing table attached to a supporting structure;

Figure 2 is a bottom plan view of the ironing table of Figure 1 detached from the supporting structure;

Figure 3 is a longitudinal sectional view of the ironing table, partially collapsed;

Figure 4 is a vertical sectional view taken substantially along the line IV—IV of Figure 1;

Figure 5 is a transverse sectional view taken substantially along the line V—V of Figure 1;

Figure 6 is a fragmental transverse sectional view, showing the manner of securing the cover for the ironing board; and

Figure 7 is a fragmentary top plan view showing an iron rest applied thereto.

As illustrated in Figure 1, the collapsible ironing table assembly of the present invention comprises an ironing board subassembly 10 which is pivotally mounted to a support structure 11 by means of a bracket subassembly 12. The ironing table subassembly is maintained in unfolded position by means of a support link 13 pivotally carried by the bracket subassembly.

The ironing table subassembly 10 comprises an ironing board 14 and a pair of longitudinally extending reinforcing strips 15 and 16 having forward portions rigidly fastened in broad sur-

2

face contact with a major portion of the longitudinal extent of the ironing board undersurface by screws 16'. The reinforcing strips extend rearwardly beyond the rear end of the board in transversely spaced relation for pivotal connection at their rear ends with the bracket subassembly 12. The intermediate rear portions 17 of the reinforcing strips are thus adapted to afford a clothes rack, as well as to space the ironing board 14 outwardly from the support structure 11 for convenience of access thereto during ironing.

As best seen in Figure 6, in order to provide convenient means for attaching an ironing pad 18 to the ironing board, a continuous groove 19 is routed in the ironing board edge. The groove cooperates with a continuous wire spring 20 to retain the cloth cover 21 in taut covering relation to the pad 18. There is thus avoided the conventional rope lacing beneath the ironing board which would obstruct the flat under faces 22 of the reinforcing strips 15 and 16 when the ironing board subassembly is detached for separate use on a table or the like.

The bracket subassembly 12 includes a transversely extending generally channel-shaped bearing bracket 24 for pivotally mounting the rear ends of the reinforcing strips. This bracket is preferably formed of a single piece of sheet metal which when bent into final shape defines a channel 25 and provides a pair of transversely spaced opposed rearwardly extending ears 26 at the ends of the channel 25 and a pair of spaced upstanding tabs 27 adjacent thereto. As shown in Figure 4, the bracket 24 is of such width as to fit between the rear ends of the reinforcing strips and a bolt 28 extends through the ends of the reinforcing strips and through the ears 26 to pivotally attach the board subassembly to the support structure. As seen in Figure 3, the upstanding tabs 27 are adapted to define with the top wall 30 of the bracket 24 a recess for retaining a cover panel (not shown) for covering the ironing table assembly when in collapsed position.

The bracket subassembly 12 also includes vertically extending brackets 31 of channel shape preferably offset or joggled at the top as indicated at 32 in Figures 1 and 3 to overlie in flat-contacting relation the lower flange 33 of bracket 24. The flange 33 and top 32 are provided with registering apertures to receive therethrough suitable fastening means such as woodscrew 34 if the bracket is to be secured to the studding of a wall. At the lower end the bracket 31 has an integral generally reversely extending open hook

35 which is adapted to be selectively closed by means of clip 36. The hook and clip are adapted to pivotally retain the bight portion 37 of the U-shaped support link 13 and are provided with registering vertical slots including slot 38 of clip 36, Figure 4, for receiving therethrough threaded fastening means such as a wood screw 39. When the screw is loosened the clip 36 will be vertically slidable on the bracket 31 for ready insertion or removal of the bight portion 37.

The outturned free ends 40 of the support link 13 are adapted to slide in longitudinal channels or guideways 41 defined by the inner side edges of the reinforcing strips 15 and 16 and the bottom surface of the ironing board. The legs of the link are resilient and are normally held together by the abutment of the outturned ends 40 in the guideway. As the ironing board subassembly is raised, the outturned link free ends 40 slide rearwardly in the channels or guideways 41 and in horizontal position of the board spring outwardly to seat in the locking sockets 42 in the reinforcing strips. To prevent wear on the strips 15 and 16, wear plates 43 are fastened to the vertical side edges of the reinforcing strips defining guideways 41 as best seen in Figure 6.

As shown in Figure 7, an ironing rest 45 may be mounted on the intermediate rear portions 46 of the reinforcing strips 47. The reinforcing strips are preferably provided with recesses 48 at their inner edges to receive the iron rest plate so that the top surface of the plate will be flush with the tops of the reinforcing strips.

It will be apparent that the bracket subassembly 12 may be separately attached to the wall and that the ironing board subassembly and support link are thereafter readily attached to the bracket subassembly or removed therefrom, the ironing board subassembly 10 being adapted for independent use in a different location, on the top of a table, for example.

It will, of course, be understood that various details of construction may be varied without departing from the principles of this invention, and it is, therefore, not the purpose to limit the patent granted hereon otherwise than necessitated by the scope of the appended claims.

I claim as my invention:

1. A collapsible ironing table assembly comprising an ironing board, a pair of reinforcing strips extending longitudinally of said ironing board in transversely spaced relation and having forward portions rigidly fastened in broad surface contact with a major portion of the longitudinal extent of the ironing board undersurface, said reinforcing strips having rear portions extending rearwardly in transversely spaced relation beyond the rear end of the ironing board, the rear strip portions having transverse aligned apertures extending through the rear extremities thereof, a transversely extending channel-shaped bracket of length substantially equal to the transverse spacing between said reinforcing strips, said bracket defining a transversely extending channel and having rearwardly extending opposed ears at the transverse ends thereof defining the ends of the channel, said ears having aligned transverse openings therethrough opening into the

channel and aligned with the apertures of said reinforcing strips, a bolt extending through the aperture of one reinforcing strip, the opening of the adjacent bracket ear, through the bracket channel, the opening of the other bracket ear, and the aperture of the other reinforcing strip, said reinforcing strips defining with the ironing board undersurface at the inner opposed edges of the forward portions of the strips opposed longitudinally extending guideways, said reinforcing strips having transverse aligned apertures opening into said guideways at the rear thereof defining locking sockets, a further bracket interconnected with said first mentioned bracket and depending therefrom, said further bracket having an open hook at the end thereof, a clip having a vertical slot for retention in vertically adjustable overlying relation to said further bracket adjacent said hook, said clip being adjustable to open and close said hook, and a U-shaped support link having a bight portion pivotally retained by said hook and clip and having outturned free ends for sliding in said opposed guideways and for expansion into said locking sockets in horizontal position of the ironing board.

2. A collapsible ironing table assembly comprising an ironing board, a pair of reinforcing strips extending longitudinally of said ironing board in transversely spaced relation and having forward portions with broad flat undersurfaces in broad surface contact with and fastened to the ironing board undersurface, said reinforcing strips having rear portions extending rearwardly in transversely spaced relation beyond the rear end of the ironing board, a bracket for pivotally mounting said rear portions of said reinforcing strips to mount said ironing board for pivotal movement about said bracket, said reinforcing strips having longitudinally extending rabbet grooves at the inner margins of the undersurfaces thereof defining with the ironing board undersurface opposed longitudinally extending guideways, said reinforcing strips having transverse aligned apertures opening into said guideways adjacent the rear thereof and defining locking sockets, a generally U-shaped support link having outturned free ends for sliding in said opposed guideways and for expansion into said locking sockets to support said ironing board in horizontal position, and a bracket for pivotally mounting the bight portion of said support link, said link outturned ends sliding forwardly in said guideways and said link pivoting about said last-mentioned bracket as said ironing board is pivoted about said first-mentioned bracket from horizontal position into collapsed position.

WALTER L. ANDERSON.
